Specification for Design.

Patented Sept. 28, 1915.

Application filed May 6, 1915. Serial No. 26,430. Term of patent 7 years.

To all whom it may concern:

Be it known that I, HORATIO B. RUGGLES, a citizen of the United States, residing at West Somerville, in the county of Middlesex and State of Massachusetts, have invented a new, original, and ornamental Design for Dairy-Lunch Chairs, of which the following is a specification, reference being had to the accompanying drawing, forming part thereof.

Of the drawings, Figure 1 represents a perspective view of the chair from the rear and one side thereof, and Fig. 2 represents a perspective view of the same from the front and opposite side thereof.

I claim:

The ornamental design for a dairy lunch chair, as shown.

HORATIO B. RUGGLES.
